2 SHEETS—SHEET 2.

UNITED STATES PATENT OFFICE.

SAMUEL H. COLEN, OF WEST CONSHOHOKEN, PENNSYLVANIA.

PUZZLE.

Application filed October 5, 1921. Serial No. 505,560.

To all whom it may concern:

Be it known that I, SAMUEL H. COLEN, a citizen of the United States, residing at West Conshohoken, in the county of Montgomery and State of Pennsylvania, have invented certain new and useful Improvements in Puzzles, of which the following is a specification, reference being had to the accompanying drawings.

10 It is the purpose of the present invention to provide a puzzle including a board and a plurality of blocks movable on the board, so that certain of the blocks may be shifted in positions usually assumed by the 15 players of a baseball nine, thereby providing what may be called a baseball puzzle.

Another purpose is to provide a puzzle including a board having a diamond, together with an outfield indicated thereon, 20 and channels conforming to the baseball diamond, and an additional channel similar in shape to the diamond and formed in the outfield, so that the plurality of blocks substantially sixty-nine in all may be shifted 25 from one position to another, whereby certain of the blocks (which constitute the players of a baseball nine) may be arranged according to the particular positions assumed by the players in the field. For instance the catcher behind the home plate, 30 the pitcher in the pitcher's box, with the several basemen properly located, with the other blocks constituting the remainder of the nine likewise in their proper positions.

35 It is still another purpose to provide a baseball puzzle of this character, wherein all the blocks constituting the players of a baseball nine are scattered in the center field, in fact irregularly arranged, as shown 40 in Figure 3, with the other blocks in the channels, it being the aim to remove one of the blocks in the outfield, and then begin the move the blocks until the blocks constituting the players can be arranged in 45 their proper places, as shown in Figure 1.

While the design and construction at present illustrated and set forth are deemed preferable, it is obvious that as a result of a reduction of the invention to a more practical form for commercial purposes, the 50 invention may be susceptible of changes, and the right to these changes is claimed, provided they are comprehended within the scope of what is claimed.

55 The invention comprises further features and combination of parts, as will be herein-

after set forth, shown in the drawings and claimed.

In the drawings:—

Figure 1 is a plan view of the board, with 60 the players of a nine properly arranged on the diamond;

Figure 2 is a sectional view on line 2—2 of Figure 1;

Figure 3 is a plan view of a diamond, 65 showing the blocks constituting a baseball nine irregularly arranged in the in or center field;

Figure 4 is a sectional view on line 4—4 of Figure 3; 70

Figure 5 is a perspective view of the board without any filler or player blocks thereon; and

Figure 6 discloses collective views of some 75 of the player blocks and filler blocks.

Referring to the drawings, 1 designates a board constituting a baseball field as a whole. The upper surface of the board, and particularly all the parts thereof which are raised are colored green, so as to represent a baseball field. The board has grooves 2 and 3, which intersect as at 4, in order to indicate the foul line on the diamond 5, which is colored blue, though not necessarily, for any other suitable color may be used. 80 As will be observed the diamond has the usual catcher's box and a red colored outline for surrounding the first, second and third bases 6, 7 and 8.

The board has the usual right and left 90 fields 9 and 10, and the usual center or outfield 11. The diamond is provided with a channel 12, which conforms to the shape of the diamond, and connected to this channel 12 is a second channel 13, which extends from the channel 12 between the first and second bases through the right field and through the out or back field 14, and then through the left field 10, and connected to the channel 12 between second and third 95 base. The center or infield has a channel 15, which communicates with the channel 12.

A plurality of blocks approximately 105 sixty-nine in all are received in these various channels, in positions as shown in Figure 1, that is when the puzzle has been worked out. Certain of these blocks designated by the characters 18, 19, 20, 21, 22, 23, 24, 25 and 26 constitute the players of a baseball 110 nine while the remaining blocks 27, which are sixty in all are used in connection with

the puzzle, and to make it difficult to arrange the blocks 18 to 26 according to the positions the baseball nine is designed to assume on the diamond. The blocks 27 engage the channels and may be shifted or moved as the case may be, in order to cause the blocks representing the players of the baseball nine to be moved. In order to permit the shifting of the blocks, in order to 5 properly arrange the blocks representing the baseball nine, one of the blocks 27 is designed to be removed from the channel to provide space for the movement of the other blocks. The several blocks constituting or 10 representing the players of a baseball nine have upstanding pins or projections 28, so that these blocks may be removed, or moved in the channel from one place to another. In other words the projections 28 constitute 15 means to be grasped by the hand of the operator, when endeavoring to manipulate and work out the puzzle.

The baseball field, as disclosed on the board is provided with grooves 29 and 30 20 indicating the coaches' boxes.

As previously stated it is the aim to arrange the blocks 18 to 26 inclusive, which constitute the players of a baseball nine, so 25 that they can be shifted to certain positions, to show where they should be positioned, when the players of a nine are on the field, as shown in Figure 1.

However when the puzzle is to be worked out, the blocks, which are to represent the 30 players of a baseball nine are first irregularly arranged on the board in the center or infield, as shown in Figure 3. After so arranging these blocks, with the other blocks 35 27 disposed as shown, one of the blocks 27 is removed from one of the channels, say for instance at 30°. After removing this block the other blocks may be shifted in various 40 directions, until the party working out the puzzle has arranged the blocks 18 to 26 in positions shown in Figure 1. While the 45 blocks 18 to 26 and the diamond are colored red, and the baseball field green, it is obvious that any other suitable color may be employed, though green is most preferable 50 for the baseball field, in order to represent grass.

The various player blocks 18 to 26 are provided with upstanding lugs 28 to be engaged by the hand of the operator, for shifting the blocks from one position to another.

The invention having been set forth, what is claimed as being useful is:

1. In a baseball puzzle, a puzzle game board having a baseball diamond comprising a channel bounding the infield, a second channel substantially of angular form with its ends connecting with the first channel be-

tween first and second bases and between second and third bases, a home plate depression connecting with said first channel, a depression of a width substantially equaling twice the width of either channel, said last mentioned depression intersecting the pitcher's box and connecting opposite portions of the first channel between home plate and first 65 base and between second and third bases, and a plurality of filler and player blocks adapted to be promiscuously arranged in said channels and depressions, whereby upon temporarily removing one or another of the 70 filler blocks at different localities, the various remaining blocks may be shifted through the channels and depressions whereby the player blocks may be arranged in positions corresponding to the respective 75 positions of ball players on a field.

2. In a baseball puzzle, a puzzle game board provided with a baseball diamond comprising channels of angular form, one bounding the infield, the other bounding the 80 outfield, the latter connecting the former between first and second bases and second and third bases, said board having a home plate depression connecting the former channel, a plurality of filler and player blocks adapted 85 to be promiscuously arranged in said channels and the depression, a second depression of a width substantially equaling twice the width of any two blocks and adapted to receive certain of said blocks, said last mentioned depression intersecting the pitcher's 90 box, and connecting opposite portions of the former channel between the home plate depression and first base, and between second and third bases, whereby upon temporarily 95 removing one or another of the filler blocks at different localities, the remaining blocks may be shifted through the channels and the depressions, and thereby result in placing the player blocks in their respective positions according to the positions of players in 100 a baseball game.

3. In a baseball puzzle, a puzzle game board having an infield diamond bound by a channel and an outfield diamond bound by 110 a channel, the latter connected to the former between first and second bases and between second and third bases, a home plate depression connecting the former channel, and a depression intersecting the pitcher's box 115 and connecting the former channel between home plate and first base and between second and third bases, said channels and depressions adapted to receive a promiscuous arrangement of filler and player blocks.

In testimony whereof I hereunto affix my signature.

SAMUEL H. COLEN.
